UNITED STATES PATENT OFFICE.

WILLIAM H. SIMMANS, OF SHELBY COUNTY, TENNESSEE.

IMPROVEMENT IN RUNNING-GEAR FOR WAGONS.

Specification forming part of Letters Patent No. **157,642**, dated December 8, 1874; application filed September 11, 1873.

To all whom it may concern:

Be it known that I, W. H. SIMMANS, of the county of Shelby and State of Tennessee, have invented a new and useful Improvement on Wagons, of which the following is a specification:

The invention relates to the construction of the coupling between the reach and front bolster or running-gear of the wagon, as herein-after described and claimed.

In the drawing, Figure 1 is a sectional elevation of the running-gear of a wagon provided with my improved coupling; and Fig. 2, a side elevation, with the front axle turned at right angles to the rear axle. Fig. 3 is a detail plan view of the coupling proper.

So far as relates to the tongue I, wheels A B, the axles G H, bolsters H H', reach C, and fifth-wheel D, there is nothing essentially novel. The tongue is rigidly connected to the front axle G, and the king-bolt F passes through the latter and its bolster H'. To permit the tongue and axle G free vertical movement or oscillation, the reach is hinged to the

U-shaped link K, and the latter fits on the vertical tubular standard E, which is firmly attached to the axle G by any suitable or preferred means, and projects upward into a recess in the under and rear side of the bolster H'. Thus the draft-strain on the rear part of the wagon is transferred to or borne by the standard instead of the king-bolt. This I do not, however, claim broadly. The link K turns freely around the standard E in the recess of the bolster, so that the front axle may assume various angles to the rear one, horizontally. This construction also allows the two parts of the running-gear to be readily disconnected when required.

What I claim is—

The combination, with the reach C, fixed tubular standard E, axle G, recessed bolster H', and king-bolt F, of the hinged U-shaped link K, as shown and described.

W. H. SIMMANS.
